UNITED STATES PATENT OFFICE.

LLOYD GILES, OF LOS ANGELES, CALIFORNIA, ASSIGNOR TO PACIFIC HEATER MANUFACTURING CO., OF LOS ANGELES, CALIFORNIA, A CORPORATION OF CALIFORNIA.

AIR-HEATER.

1,144,469.

Specification of Letters Patent. Patented June 29, 1915.

Application filed August 18, 1914. Serial No. 857,409.

To all whom it may concern:

Be it known that I, LLOYD GILES, a citizen of the United States, residing at Los Angeles, in the county of Los Angeles, State 5 of California, have invented a new and useful Air-Heater, of which the following is a specification.

The invention relates to heaters, and more particularly to air heaters, in which 10 a supply of cold air is drawn into a heater, heated therein, and discharged into the space to be heated.

The principal object of the invention is to provide a heater which will be small and 15 compact, and which may be installed in partially inclosed rooms or porches, such as are usually found in warm climates. There have been, and are being erected throughout the United States, especially in the portions 20 thereof having a warm climate, large numbers of small one story dwellings known as bungalows. When built in such locations, and especially in California and Arizona, bungalows are small, low in cost, 25 and inexpensive and efficient heating means for such bungalows are in great demand. In these climates for the greater portion of the year heat is required only at certain 30 times of the day, and gas forms a convenient and inexpensive means for heating them if it is properly applied.

A further object of the invention is to provide a gas heater which shall be low in cost, and particularly adapted for use in 35 bungalows, being installed on the screen porch thereof, without the necessity for extensive cellar excavations such as are necessary where many of the common forms of heaters are used.

40 The particular form of my invention illustrated herewith is also applicable to apartment house heating in similar latitudes, one of these heaters being conveniently located in each suite of apartments, 45 and being wholly under the control of the tenant thereof.

A further object of my invention is to provide a heater which shall be economical to operate, and which will at the same time 50 thoroughly ventilate the space to be heated. By installing the ordinary type of closed stove in the room to be heated, a very efficient heating of the air is accomplished, but there is ordinarily no ventilation produced by such a stove. The air in the room

is simply heated and reheated without a supply of fresh air being brought in. The use of open fire places or grates is quite efficient from a ventilation standpoint, foul air being taken from the room and sent up 60 the chimney, through which most of the hot gases also escape without doing any considerable amount of useful work. By using my invention heating efficiencies equal to or in excess of those obtained by the use of 65 stoves are obtained, and at the same time a thorough ventilation is provided, large supplies of fresh air being constantly forced into the space to be heated. To produce this high heating efficiency it is necessary to provide a large heating area, and it is necessary 70 to evenly distribute the heating gases and the air to be heated over such areas. In the production of such a heater it is further necessary to confine the hot gases and products 75 of combustion so that no mixture of the products of combustion with the air to be heated will take place, and it is further necessary that the means employed for the separation be constructed so as not to be 80 affected by expansion or contraction, or the corroding influence of the gases.

All these objects and advantages are accomplished in my invention as will be evident from the following specification and 85 drawings.

Referring to the drawings which are for 90 illustrative purposes only: Figure 1 is a plan view of one form of my invention. Fig. 2 is an elevation, portions of the heater being shown cut away and in section to better illustrate the internal construction. Fig. 3 is a section on the plane x^3-x^8 of Fig. 1 looking in the direction of the arrows. Fig. 4 is a section on the plane x^4-x^4 of Fig. 3 95 looking in the direction of the arrows. Fig. 5 is a section on the plane x^5-x^5 of Fig. 3 looking in the direction of the arrows. Fig. 6 is a section on the plane x^6-x^6 of Fig. 4 100 looking in the direction of the arrows.

In the form of my invention illustrated in the drawings an outer casing 1 surrounds a cell structure 2 which is fed with hot gas from a combustion chamber 3 in which is located a burner 4. A fan 5 driven by a 105 motor 6 draws the outside air in through a grating 7 in the top of the casing 1, and a flue 8 draws off the products of combustion from the cell structure 2. A hot air pipe 9 passes to registers located in the floor, walls, 110

or at convenient points in the area to be heated.

The outer casing 1 is preferably formed of sheet iron and is divided by the cell structure 2 into a wedge shaped inlet chamber 10 and a wedge shaped outlet chamber 11. The cell structure 2 is formed of a non-corrosive metal preferably ingot iron welded together into the form shown. It consists of thin walls forming a series of passages 12 providing an open communication between the chambers 10 and 11. Walls between the passages 12 form primary ascending passages 13, descending passages 14, and 15 secondary ascending passages 15.

The combustion chamber 3 is located inside the outer shell 16 of the cell structure 2, dead air spaces 17 and 18 being formed by a diaphragm 19 between the shell 16 and the casing 1 for the purpose of heat insulating the cell 2. Gas chambers 20 and 21 are provided in the shell 16 at either side of the combustion chamber 3, the gas chambers 20 and 21 having openings to the outer air 25 closed by spring actuated explosion doors 22 and 23.

The gas burner 4 is placed in the combustion chamber 3 and is supplied with gas from a gas pipe 25, suitable controlling valves and air mixing devices being supplied in combination with said burner and pipe according to the usual practice. A pilot flame burner 26 is provided so that the heater can be regulated without danger of 35 entirely cutting off the flame.

The fan 5 revolves in an involute casing 27, the interior of which is in open communication with the hot air pipe 9. One side of this casing 27 has an opening 28 40 providing an open communication between the center of the fan 5 and the chamber 11. The fan 5 consists of a shaft 29 to which is rigidly secured a runner 30 having a plurality of flat radial blades 31. The shaft 29 turns freely in bearings 32 between which is a reservoir 33 in which oil is placed and from which the oil is fed to the shaft 29 by means of oil rings, or any other convenient means. The motor 6 is preferably connected to the shaft 29 through pulleys 34 and 35 and a belt 36.

The method of operation of the invention is as follows: Gas is admitted to the chamber 3 through the pilot tube 26 and ignited 55 at the inner end of said tube. The motor 6 is started and the fan 5 is rotated at a high rate of speed. The centrifugal effect of the blades 31 throws the air outwardly into the casing 27 drawing it inwardly through the opening 28 from the chamber 11. The air taken from the chamber 11 is replaced by air drawn through the grating 7, the chamber 10, and the passages 12. Gas being admitted to the burner 2, is ignited by the 60 pilot flame, and the hot gases pass upwardly 65

through the passages 13 and downwardly through the passages 14 into the chambers 20 and 21, from thence passing upwardly through the passages 15 to the flue 8. In their passage through the cell structure 2, 70 these hot gases heat the walls of the passages 12 through which the fresh air passes from the chamber 10 to the chamber 11.

If an explosion takes place in the chambers 20 and 21 any excess pressure therein is 75 relieved by the doors 22 and 23.

The cell structure is welded thoroughly together and its form is such that it forms a multiple truss enabling it to stand high internal pressures such as are produced when 80 a gas explosion is produced therein.

In practice each vertical row of the openings 12 is inclosed in a single sheet of metal, which forms a double thickness at the points 50 so that any pulling apart of the seams by 85 expansion at this point will not allow the products of combustion to leak out of the cell.

The cell structure 2 is inclined in the outer shell 1, the chamber 10 being smallest at 90 the bottom, and the chamber 11 being smallest at the top. The object of this variation in cross section is to produce a uniform movement of the air to be heated through the chambers 10 and 11, and the 95 passages 12.

The cell structure 2 consists more particularly of a front wall 55, the lower end 56 of which extends forwardly to the front wall 57 of the outer casing 1 of the heater, and a rear wall 58 which extends downwardly to the bottom wall 59 thereof and connects at its upper end with the top wall 60 thereof. Arranged diagonally and extending through the front wall 55 and rear wall 58 are a series of division walls 61 bent to form the diagonally disposed air passage 12 heretofore referred to, two of said walls 61 being extended downwardly as indicated at 62 and connected at the bottom as indicated at 63 to 105 form the side and bottom walls of the combustion chamber 3. As heretofore referred to the air passages are arranged in vertical rows and the walls 61 thereof are connected as indicated at 50, thereby forming the passages 115 13, 14, and 15, which together form tortuous conduits from the combustion chamber 38 to the flue. The gas chambers 20 and 21 are formed by the walls 61 of the lowermost air passages 12, the extension 62 of said walls, 120 the bottom wall 59, and side walls of the shell 16, said gas chambers communicating with the tortuous conduits referred to.

The invention illustrated in the drawings and described in the previous specification 125 has been developed as an improvement on the structure shown in Letters Patent No. 1,076,209, issued October 26, 1913, to Edward C. Kent, George A. Lyster, and myself. The principal elements of novelty in 130

the structure shown and described in this application over the earlier application are as follows: First, the particular and peculiar form of cell structure, whereby a very long heating path is obtained and whereby a very rigid and permanent construction is worked out. Second, the inclination of the cell structure so that a wedge shaped inlet chamber is provided upon one side of the 10 cell structure, and an inverted wedge shaped outlet is provided on the other. This construction when combined with inclined openings between these chambers results in a heater in which there is a very uniform 15 movement of the air to be heated, and a very perfect distribution of this air over the heating surfaces. Third, the entirely enclosed form of combustion chamber placed in the center of the shell with a gas chamber 20 on either side thereof, and in the use of explosion doors for relieving excess pressures from these gas chambers.

I claim as my invention:

1. An air heater comprising an outer casing having a flue extending through the top thereof and an air inlet opening, a combustion chamber in said casing, a cell structure in said casing arranged to form an air inlet chamber at the front thereof and an air 25 outlet chamber at the rear thereof both within said casing, a series of walls extending across said cell structure and forming a series of substantially horizontally disposed air passages connecting said air inlet passage and said air outlet passage, the walls of said air passages being connected to form tortuous conduits within the cell structure from the combustion chamber to said flue and consisting of a series of ascending and 30 descending passages for the heated gases, and means for withdrawing the air from the air outlet chamber.

2. An air heater comprising an outer casing having a flue at the top thereof and an air inlet opening, a combustion chamber in said casing, a cell structure in said casing arranged to form a downwardly converging air inlet chamber between the front wall thereof and the front wall of said casing 45 and a downwardly diverging air outlet chamber between the rear wall thereof and the rear wall of said casing, said cell structure having a series of passages extending therethrough and connecting the air inlet chamber with the air outlet chamber and having a series of communicating tortuous ascending and descending passages forming conduits for the heated gases from said combustion chamber to said flue, and means for 50 withdrawing air from said air outlet chamber.

3. An air heater comprising an outer casing having a flue at the top thereof and an air inlet opening, a combustion chamber in 55 said casing, a cell structure in said casing ar-

ranged to form an air inlet chamber at the front thereof and an air outlet chamber at the rear thereof, said cell structure having a series of diagonally disposed passages therethrough connecting the air inlet chamber with the air outlet chamber and having a series of tortuous ascending and descending passages therethrough forming conduits for the heated gases from said combustion chamber to said flue, and means for withdrawing air from said outlet chamber. 70 75

4. An air heater comprising an outer casing having a flue extending through the top thereof and an air inlet opening in the top thereof, a shell mounted in said outer casing having a combustion chamber in the lower portion thereof, the front wall of said shell being arranged at an angle with the front wall of said casing to form a downwardly converging air inlet chamber therebetween, the rear wall of said shell being arranged at an angle to the rear wall of said outer casing to form a downwardly converging air outlet chamber therebetween, a series of division walls extending through said shell from the front to the rear thereof forming a series of air passages therethrough in open communication with the air inlet and air outlet chambers, said division walls being joined vertically between said air passages thereby forming a series of ascending and descending passages forming continuous conduits from said combustion chamber to said flue, and means for withdrawing the air from said air outlet chamber. 80 85 90 95 100

5. An air heater comprising an outer casing having an air opening at the top thereof, a shell mounted in said casing having a combustion chamber in the lower portion thereof and a flue at the top thereof extending through the top of said casing, said shell having front and rear walls spaced apart respectively from the front and rear walls of said casing to form an air inlet chamber in the front portion and an air outlet chamber in the rear portion of said casing, a series of division walls extending through said shell from the front to the rear thereof and forming a series of vertical rows of communicating passages between said air inlet and air outlet chambers, said division walls being connected vertically between said air passages and thereby forming vertically ascending and descending passages 105 110 115 120 therebetween, said passages being connected to form tortuous conduits from said combustion chamber to said flue, and means for withdrawing air from said air outlet chamber. 125

6. An air heater comprising an outer casing having an air inlet opening at the top thereof, a shell mounted in said casing and having a flue extending through said casing, said shell having front and rear walls 130

- spaced apart respectively from the front and rear walls of said casing and arranged at an angle thereto to form a downwardly converging air inlet chamber in the front portion of said casing and a downwardly diverging air outlet chamber in the rear portion of said casing, a series of division walls extending through said shell from the front to the rear thereof and forming a series of vertical rows of air passages connecting said air inlet chamber and said air outlet chamber, said division walls being connected vertically between said air passages, extensions on two of said division walls connected at the bottom and thereby forming a combustion chamber in said shell and a gas chamber on the outer side of each

extension within said shell, means for relieving the pressure in each gas chamber, said division walls forming tortuous conduits between said combustion chamber and said flue in open communication with the respective gas chambers, and consisting of a series of ascending and descending passages, and means for withdrawing air from said air outlet chamber.

In testimony whereof, I have hereunto set my hand at Los Angeles, California, this 13th day of August, 1914.

LLOYD GILES.
